UNITED STATES PATENT OFFICE.

ALFONS H. NEULAND, OF JERSEY CITY, NEW JERSEY.

DYNAMO-ELECTRIC MACHINE.

Application filed August 24, 1920. Serial No. 405,577.

To all whom it may concern:

Be it known that I, ALFONS H. NEULAND, a citizen of Russia, residing at Jersey City, in the county of Hudson and State of New Jersey, have invented certain new and useful Improvements in Dynamo-Electric Machines, of which the following is a full, clear, and exact description.

My invention relates to electro-magnetic power transmissions and is particularly adapted for use in connection with internal combustion engines; as in automobiles, railway cars and hoists, and wherever it is desired to change the constant speed of a prime mover into a variable or adjustable speed.

One object of my invention is to provide for a transmission of light weight and high power. Another object is to provide for a simple control and unitary construction. Another object is to provide for electric braking of the driven vehicle or apparatus. Still another object is to provide such an apparatus with stationary brushes only and one which is capable of charging a battery and of cranking or starting the prime mover. Another object is to provide for a special reversing gear to operate in connection with such a transmission. Still other objects and advantages of my invention will appear from the following description:

In electrical transmissions as at present applied to automobiles, their speed and torque are varied by a change in the field strength. When weakening the field, it is known that the current, for a given torque is increased in inverse proportion. These heavy currents render commutation difficult and make for inefficiency or else necessitate an increase in size and weight of the machine.

I seek to overcome these difficulties in my present invention by maintaining a powerful field and increasing the field strength with increasing loads. This insures a comparatively light current even when the machine carries heavy loads and permits an economic construction of light weight. Furthermore, my present invention permits the use of low voltage which is of importance in securing good commutation and a light weight controller.

Speed and torque changes are obtained by what is virtually a two part armature; one part arranged rotatably and the other

stationary and so that the currents in both are in phase with each other. The stationary part of the armature is so arranged that a portion or all may be cut out of the circuit. The rotatably arranged field element is acted on, depending upon the controller position, by the sum of the currents in the stationary and rotatable armatures, by their difference, when the former is reversed, or by the current in the rotatable armature alone.

This regulation and operation is brought about by the use of stationary brushes only and is made possible by the special commutating arrangement and the series relation between the field and the two armature windings as well as by the special construction of the rotating armature and the arrangement of the elements with respect to each other so that they are acted on and traversed by a common magnetic flux.

My invention also comprehends various features of mechanical construction, details and arrangement of parts, as will herein-after more fully appear.

I shall now describe the illustrated embodiment of my invention and shall thereafter point out my invention in claims.

Fig. 1 is a partial longitudinal section and a partial side elevation of a complete transmission embodying my invention.

Fig. 2 is a segment of a transverse section, showing the magnetic structure and particularly the shape of the rotatable armature laminations.

Fig. 3 is a diagram of the electric circuits including the controller contacts by means of which the connections are changed.

Fig. 4, "x," "y," "z," are diagrams showing the change in connections when the controller is in the cranking position.

Fig. 5 "a," "b," "c," "d," is a representation of the relative strength, position and direction of the currents in the respective elements with the controller in the several positions.

The transmission which I have selected for illustration in the drawings is adapted to automobiles propelled by an internal combustion engine 1, in that the driving or primary armature 2, serves as the fly wheel, and is rigidly connected to the crank shaft 3. The secondary or driven field element 4 is connected to the propeller shaft 5 which is supported at one end by an extension of

the armature spider 6 through the ball bearing 7. This bearing is located in or near the longitudinal center of the field element permitting a considerable wear in the engine bearings and a small air gap between the two rotating elements without danger of one rubbing against the other. The drive shaft is supported near its other end by the bearing 8, which, in turn, is mounted 10 in a bearing seat of the stationary bracket 9; the bracket being secured to the housing 10, which carries the stationary armature element 11 consisting of a laminated ring provided on its inner face with slots 12, and in which is embedded the distributed winding 13.

The field element is provided with eight pole pieces 14, each carrying a field coil 15. The field element is in inductive relation to 20 each of the armature windings while the armatures cooperate with each other in their action on the field element. It will be particularly noted and it is of importance that the field is inductively related to the stationary armature, although the rotating armature separates one from the other. The special construction of the armature laminations provides for this relation in that it is built up of sectors 16 with the spaces 17 between them. Substantially all the flux from 30 the field is in this way directed radially through the rotatable armature and reaches and cuts the stationary armature winding. These spaces between the sectors also serve 35 as coil receiving slots and the coils are preferably arranged on the outer circumference of the rotating armature. The sectors 16 are provided with a hole at the inner face fitting over the metal rods 18, the rods being 40 securely pressed into armature spider 6, and the other end of the rods being forced into and insulated from the ring 19. The rotatable armature winding 20 is arranged in the slots 17 and connected to the commutator 21. Stationary polyphase brushes 22, preferably three phase, are secured to the engine casing and wipe the commutator 21.

A commutator 23 is also provided for the field; it is attached to and rotates with the 50 field element. This commutator is of special construction and has one and preferably wide segment 24 per pole, as shown in the diagram of Figure 3, in which, for the sake of simplicity, the commutator is shown as 55 for a two pole machine. Between each two of the wide segments are a plurality of narrow segments 25, and a suitable resistance separates the adjacent segments. This field commutator is wiped by stationary poly- 60 phase (preferably three phase) brushes 26. Connecting the adjacent segments of the field commutator are resistances, those nearest to the wide segments being low and those farthest away from them being high, and 65 the two ends of the field winding are con-

nected to the wide segments. Due to the fact that the combined resistances which bridge the wide segments and also shunt the field windings are much higher than the resistance of the field winding, substantially 70 all the current at the brushes 26 transverses the field winding. In this way the field winding is in series relation to the stationary and rotatable armature windings.

Referring to Fig. 3 with the controller 75 drum C in the off position all circuits are open, serving to interrupt the flow of power from the engine to the rear wheels. The field winding, in this position of the controller, is short circuited by the short circuiting contactor S, which also serves to avoid or minimize sparking at the controller contacts as it is moved from one step to the other. This is accomplished by first short circuiting the field winding, then 80 opening the power circuits; a further movement makes the connections for the new step and then opens the field short circuit and thereby instantly permits the machine to 85 pick up with the newly established connections.

With the controller on "low" or first speed the connections are such that the entire stationary armature winding is in circuit, the corresponding current strengths and relations being indicated in Figure 5^a. This is the position for highest speed reduction and greatest torque the sum of the stationary and rotary armature currents acting upon the field. With turns in series on the stationary armature double that on the rotary armature, the torque on the driven field 95 will be substantially triple that applied by the driving armature.

With the controller on "second", only a 100 fraction of the stationary armature is included in the circuit. Fig. 5^b is the corresponding representation and shows the reduced torque upon the field element in that the sum of the two armature forces has 105 been decreased. By cutting out a portion of the stationary armature winding the counter potential, resulting from a rotation of the field with respect to it, is decreased and the speed of the field element is correspondingly increased.

Next the controller is moved to "direct" in which position the stationary armature winding is entirely cut out, as indicated in Fig. 5^c. The rotating armature winding is 110 now directly, and in series relation, connected to the field winding through the two commutators and the two sets of stationary polyphase brushes. The device now operates virtually as a clutch since both the field 115 element and the armature are rotating at nearly the same speed, and requiring only a small slip to force the load current through the circuit. It will be noted that unlike the well known D. C. clutch the 120 125

brushes here are stationary, and unlike the type of clutch or motor generator having stationary D. C. brushes, a stationary field and a high potential at the brushes, the potential in this clutch of my invention is low, resulting in good commutation and a wide range of regulation.

The fourth step and "high" is considered of importance in that it permits the driven field element to operate at a greater speed than the engine or driving armature. A considerable economy in engine fuel is obtained by thus operating the engine near full load and at low speed. As shown by Figure 3 and Figure 5^a, a portion of the stationary armature winding and the current therein, although in phase with, is reversed against the current in the rotating armature, the difference between the two currents representing a decreased torque upon the field element. The rotation of the field element, however, against the reversed winding generates a potential which maintains a current in the circuit at zero slip between field element and rotating armature and causes the field element to turn faster than the armature.

Provision is made for electric braking. There are two brake positions in the controller shown in Figure 3. The first and nearest to the "off" position includes a portion of the stationary armature winding and is connected to the field brushes in reverse direction or the same as for "high" operation, the brushes 22 on the rotating armature being disconnected. The brake connection also includes the resistances 27, the device now operating as a generator and the energy represented by the momentum of the moving parts being consumed by the said resistance. The rotating armature, although separating the two generating elements in this instance, does not prevent this function due to the special construction employed.

In the second brake position the entire stationary armature winding is included in the circuit and produces an increased braking action.

Fig. 4^x shows the normal relation of the stationary to that of the rotating armature winding. When the controller is moved to the position for cranking the engine I arrange the stationary and rotating armature windings, which are used for cranking purposes, as shown in Fig. 4^y. Only two of the armature brushes are used while all the stationary armature windings are employed. The arrangement and connection of the circuits in this way is important and enables the use of a moderate size battery to produce the necessary cranking torque. In Fig. 4^x, an alternate scheme of connections is shown differing from the first in that the stationary winding has multiple relation to the armature.

Arrangement is made for charging the battery 28 which is connected across the field 15 through the slip rings 29 and 30 and closed by means of the automatic switch 31 when the current in the field winding reaches a certain predetermined strength and the voltage drop across the field winding reaches a value approximating that of the battery. The series winding 32 on the switch, besides preventing a discharge of battery through the field when the charging potential is low, opens the battery circuit and prevents a flow of battery current through the short circuit contactor S, when the latter acts to short circuit the field winding during changes of the controller.

The resistance 33 permits a flow of battery current through the field when the controller is moved to the braking positions and insures an instantaneous pick up in the braking action.

In some instances it may be preferred to drive the field element; the rotating armature serving as the driven or secondary element. In such event, however, it is not practical to obtain a torque on the driven in excess of the driving element. The direct drive as shown by c of Fig. 5 will produce the greatest torque and lowest speed, that is, practically a 1 to 1 ratio of torque and speed, thus serving to increase the speed to double, triple or more above the driver or field element with a corresponding diminution in the driven torque. This is because the driving field element exerts a torque on the rotating and also a torque on the stationary armature winding, generating therein a potential which serves to drive the armature at a speed exceeding that of the driving field element, so that with as many turns on the stationary armature as on the rotating armature the latter will rotate at about twice the speed of the field.

The shaft 5 extends beyond the transmission bearing 8 and is splined to receive the sliding bevel gear 34, engaging, when in position for reverse, the idler gear 35 causing the stub shaft 36 to rotate in reverse direction. When the lever 37 is brought to the right, the gear 34 is disengaged from the idler 35, and the clutch 38 connects the driven shaft 5 directly to the shaft 36 for forward rotation.

It is obvious that various modifications may be made in the construction shown in the drawings and above particularly described within the principle and scope of my invention.

I claim:

1. An electro-magnetic power transmission device comprising a stationary armature winding, a rotative armature including a commutator and winding and a field member including a commutator and a wind-

- ing inductively related to both armature windings, and means for connecting the three windings in series, said means including a set of polyphase brushes for each commutator.
2. A dynamo-electric machine comprising a rotative armature including a commutator and winding, a rotative field member including a commutator and winding and a set of polyphase brushes wiping each commutator.
3. A dynamo-electric machine comprising a rotative armature including a commutator and winding, a rotative field member including a commutator and winding in inductive relation to the armature winding, and means including a set of polyphase brushes for each commutator arranged to connect the two windings in series relation.
4. A dynamo-electric machine including a rotative armature including a commutator and winding, a rotative field member including a commutator and winding in inductive relation to the armature winding, a set of polyphase brushes for each commutator, and means for electrically connecting the two sets of brushes.
5. A dynamo-electric machine comprising a rotative armature including a commutator and winding, a stationary armature including a winding, a rotative field member including a commutator and winding, and means including a set of polyphase brushes for each commutator arranged to connect the three windings in series relation.
6. An electro-magnetic power transmission device comprising a rotative armature including a commutator and winding, a stationary armature including a winding, a rotative field member including a commutator and having a winding inductively related to both armature windings, and polyphase brushes wiping both commutators and arranged to be electrically connected to the stationary armature winding.
7. An electro-magnetic power transmission device comprising a rotative armature including a commutator and winding, a stationary armature including a winding, a rotative field member including a commutator and having a winding inductively related to both armature windings, polyphase brushes wiping both commutators and arranged to be electrically connected to the stationary armature winding, and a controller arranged to vary the turns in series in the stationary armature winding.
8. An electro-magnetic power transmission device comprising a polyphase stationary armature winding, a rotative armature including a commutator and winding, a rotative field member including a commutator and having a winding inductively related to both armature windings, stationary brushes wiping the armature commutator and arranged to be electrically connected to one end of the respective phases of the stationary armature winding, stationary brushes wiping the field commutator and arranged to be electrically connected to the other end of the respective phases of the stationary
- and arranged to be electrically connected to one end of the respective phases of the stationary armature winding, and stationary brushes wiping the field commutator and arranged to be electrically connected to the other end of the respective phases of the stationary armature winding.
9. An electro-magnetic power transmission device comprising a polyphase stationary armature winding, a rotative armature including a commutator and winding, a rotative field member including a commutator and having a winding inductively related to both armature windings, stationary brushes wiping the armature commutator and arranged to be electrically connected to one end of the respective phases of the stationary armature winding, stationary brushes wiping the field commutator and arranged to be electrically connected to the other end of the respective phases of the stationary armature winding, and a controller arranged to vary the turns in series in the stationary armature winding.
10. An electro-magnetic power transmission device comprising a stationary armature winding, a rotative armature winding and a rotative field member including a winding inductively related to both armature windings, means for connecting the three windings in series comprising two sets of polyphase brushes making electrical connection between the stationary and rotative armature windings and between the stationary armature and field windings, and means for reversing a part of the stationary armature winding.
11. An electro-magnetic power transmission device comprising a rotative armature including a commutator and winding, a stationary armature including a winding, a rotative field member including a commutator and having a winding inductively related to both armature windings, polyphase brushes wiping both commutators and arranged to be electrically connected to the stationary armature winding, a controller arranged to vary the turns in series in the stationary armature winding, and means for reversing a part of the stationary armature winding.
12. An electro-magnetic power transmission device comprising a polyphase stationary armature winding, a rotative armature including a commutator and winding, a rotative field member, including a commutator and having a winding inductively related to both armature windings, stationary brushes, wiping the armature commutator and arranged to be electrically connected to one end of the respective phases of the stationary armature winding, stationary brushes wiping the field commutator and arranged to be electrically connected to the other end of the respective phases of the stationary

- armature winding and means for reversing a part of the stationary armature winding.
13. A dynamo-electric machine comprising a rotative field member including a field winding and a commutator connected thereto, a stationary armature including a winding surrounding and spaced from the field member, and a rotative armature disposed in the space between the stationary armature and field member and having a plurality of circumferentially spaced laminated magnetic sectors and a drum winding disposed between the sectors and including a commutator connected to the drum winding, and means for electrically connecting the stationary armature winding to the two commutators. 10
14. A dynamo-electric machine comprising a rotative field member, a stationary armature including a winding surrounding and spaced from the field member, and a rotative armature disposed in the space between the stationary armature and field member and having a plurality of circumferentially spaced laminated sectors and a drum winding disposed between the sectors, whereby both armature windings are cut by the field flux, and means for connecting the three windings in series including a commutator for each rotative member and a set of stationary brushes for each commutator. 20
15. A dynamo-electric machine comprising a rotative field member, a stationary armature including a winding surrounding and spaced from the field member, and a rotative armature disposed in the space between the stationary armature and field member and having a plurality of circumferentially spaced laminated sectors and a drum winding disposed between the sectors, whereby both armature windings are cut by the field flux, means for connecting the three windings in series including a commutator for each rotative member and a set of stationary brushes for each commutator, and a controller arranged to vary the turns in series in the stationary armature winding. 30
16. A dynamo-electric machine comprising a rotative field member, a stationary armature including a winding surrounding and spaced from the field member, and a rotative armature disposed in the space between the stationary armature and field member and having a plurality of circumferentially spaced laminated sectors and a drum winding disposed between the sectors, whereby both armature windings are cut by the field flux, means for connecting the three windings in series including a commutator for each rotative member and a set of stationary brushes for each commutator, a controller arranged to vary the turns in series in the stationary armature winding, and means for reversing a part of the stationary armature winding. 40
17. An electro-magnetic power transmission device comprising a rotative armature including a commutator and winding, a stationary armature including a winding, a rotative field member including a commutator and having a winding inductively related to both armature windings, a set of stationary brushes wiping each commutator, both sets being arranged to be electrically connected to the stationary armature winding, a controller arranged to vary the turns in series in the stationary armature winding, and means for short circuiting the field winding when shifting the controller from one operative position to another. 50
18. An electro-magnetic power transmission device comprising a rotative armature including a commutator and winding, a stationary armature including a winding, a rotative field member including a commutator and having a winding inductively related to both armature windings, a set of stationary brushes wiping each commutator, both sets being arranged to be electrically connected to the stationary armature winding, a controller arranged to vary the turns in series in the stationary armature winding, means for short circuiting the field winding when shifting the controller from one operative position to another, a storage battery adapted to be connected across the field winding for charging, and automatic means for interrupting the charging circuit when the field winding is short circuited. 60
19. A dynamo electric machine comprising a stationary armature winding, a rotative field member including a field winding and a commutator connected thereto, polyphase brushes wiping said commutator and adapted to connect the two windings in series relation, and controlling means operative to reverse one winding with respect to the other and thereby establish braking relation between the windings. 70
20. An electro-magnetic power transmission device comprising a stationary armature winding, a rotative armature winding and a rotative field member including a winding inductively related to both armature windings, means for connecting the three windings in series including a commutator for each rotation winding and a set of stationary brushes for each commutator, and braking means including a resistance and a controller operative to reverse a part of the stationary armature winding and simultaneously to include the resistance in the circuit and exclude the rotative armature winding from the circuit. 80
21. An electro-magnetic power transmission device comprising a rotative armature including a commutator and winding, a stationary armature including a winding, a rotative field member including a commutator and having a winding inductively related 90

to both armature windings, a set of stationary brushes wiping each commutator, both sets being arranged to be electrically connected to the stationary armature winding, 5 and braking means including a resistance and a controller operative to reverse a part of the stationary armature winding and si-

multaneously to include the resistance in the circuit and exclude the rotative armature winding from the circuit.

10
